HEAD FOR A HYDRAULICALLY OPERATED STAPLE DRIVER OR SIMILAR ARTICLE

Herbert W. Marano, Summit, N. J., assignor to Wilson Jones Company, Chicago, Ill., a corporation of Massachusetts

Application November 16, 1955, Serial No. 38,928

Term of patent 14 years

(Cl. D74—1)

Figure 1 is a side elevational view of the head for a hydraulically operated staple driver or similar article, showing my new design;

Figure 2 is a top plan view thereof; and

Figures 3 and 4 are, respectively, front and rear elevational views thereof.

I claim:

The ornamental design for a head for a hydraulically operated staple driver or similar article, as shown.
